His Attorney.

UNITED STATES PATENT OFFICE

JOHN C. SAMPSON, OF ST. LOUIS, MISSOURI, ASSIGNOR OF ONE-HALF TO JULIAN E. SAMPSON, OF UNIVERSITY CITY, MISSOURI

ATTACHMENT PLUG

Application filed September 7, 1928. Serial No. 304,407.

This invention pertains to electric attachment plugs, such as are used at the end of a flexible cord for the purpose of connecting an electrical appliance to the supply circuit.

5 One of the objects of this invention is to provide an attachment plug having incorporated therein a fuse member by which the appliance served thereby may be provided with a removable and renewable fuse member, 10 which may be assembled therewith and which may be easily renewed when a fuse has been blown.

Another object is to provide such a plug with an arrangement of contacts, such that 15 it is impossible to assemble the device in the wrong manner.

Another object is to provide such a plug so arranged that it is impossible to use the plug in the normal manner without a proper 20 fuse mounted thereon.

Another object is to provide such a plug with a fuse-holding member so arranged that the fuse therein may be easily replaced when blown.

25 Another object is to provide such a plug with an assembled fuse member so arranged that the fuse member is held in assembled relation rigidly enough so that it will not be separated by the operation of removing the 30 plug from its socket or receptacle.

Further objects will appear from the following description, taken in connection with the accompanying drawing, in which—

Figure 1 is a side view of an attachment 35 plug embodying this invention;

Figure 2 is a longitudinal section, taken on line 2—2 of Figure 1;

Figure 3 is a side view of the base portion only;

40 Figure 4 is a similar view of the body portion;

Figure 5 is a transverse section, taken on line 5—5 of Figure 2; and

Figure 6 is a perspective detail of the fuse 45 assembly.

Referring to the drawing, 1 designates a base portion, which may be constructed of molded insulation or any other suitable material, and is provided with a central passage 50 2 through which the flexible cord or other cir-

cuit conductor may be led to the interior parts. Mounted in the base 1 is an elongated contact blade 3, which may be provided with recesses 4 adapted to engage a suitable spring catch in the receptacle or socket into which the blade may be inserted. The contact blade 3 is of ordinary construction, such as is used in attachment plugs of the push type, except that it is considerably elongated for a purpose which will presently be pointed out. 55 This contact may be attached to the base 1 by means of one or more rivets 5, or other suitable fastenings. The base 1 is also provided with an additional contact blade 6 set opposite the blade 3 in the usual manner and also secured by rivets 5 or similar fastenings. In accordance with the present invention, however, the blade 6 has its end formed with a curl 7, as shown more clearly in Figure 3, and is set in an angular position with respect to 60 the contact 3. In the arrangement shown in the drawing, the blade 6 is set at right angles to the blade 3. The former blade is also considerably shorter than the latter.

A body portion 8, also of molded insulation 75 or similar material, provides a fuse member on which the fuse is mounted. This body member is constructed with an annular flange 9 and has its body portion cut away, as shown in Figure 5, to accommodate contact elements 80 10 and 11. The contact element 10 comprises a flat plate secured in place on the body 8 by a screw 12 or other suitable fastening, and has its end portions bent upwardly, as shown at 85 13 (Figure 2). These upwardly bent portions provide a clip or socket adapted to receive the curled end 7 of the contact 6 when the base and the body are assembled together, as illustrated in Figure 2. The clip portions 13 are provided with struck up knobs or lugs 90 14 adapted to engage in the open ends of the curled part 7, so as to hold the contact 6 securely in their grip when the parts are assembled as in Figure 2. The contact element 11 may have the form of a screw or similar fastening, which serves a double purpose of holding a contact blade 15 in place on the body 8 and also providing a terminal for the fuse strip 16. The fuse 16 passes from the terminal 11 around the circular portion of the body 95 100

8 and its other end is attached by soldering or otherwise to the contact 10. The body 8 is provided with a cover or cap 17 having a flange 18 surrounding the circular part of the body portion 8 and enclosing the fuse 16. The flange 18 may be provided at one side with a window 19 opposite the reduced portion 20 of the fuse 16, in order that an observer may tell, by looking through the window 19, whether or not the fuse is intact. A strip of mica 21 or similar material may be placed within the flange 18 so as to protect the fuse at the window 19 and at the same time permit inspection thereof. The assembled body and cap are provided with an opening 22, passing through both of them, adapted to receive the blade 3 when in assembled relation. This blade passes clear through the body and projects from the opposite side in a position parallel to the blade 15. These two blades are proportioned to fit a standard push plug receptacle. The cap 17 may be secured in place by a screw 23 or similar fastener.

When this plug is in use, the flexible cord or other circuit conductors are led through the passage 2 and connected to the contacts 3 and 6 in the usual manner. When this has been done, the body 8, assembled with its fuse, is applied to the base 1 by slipping the blade 3 through the opening 22 and engaging the blade 6 in the socket 13. This not only places the parts in assembled relation and secures them so, but also establishes the necessary electrical circuit connections. The blade 3 passes clear through the body, while the blade 6 contacts with the clip 13 at one end of the fuse 16, whose other end is connected to the blade 15. When thus assembled, the device may be used as an ordinary push plug in any standard socket or receptacle of the same type.

It will be noted that this invention provides a number of advantageous features. The body portion provides a renewable fuse member, which may be detached from the base 1 when the fuse has been blown and a new one applied. It is also convenient to renew the fuse 16 by simply removing the cap 17 and replacing the strip of fuse material with a new strip. When the body portion has been removed, the remaining portion is not usable as a push plug; since, in the first place, the blade 3 is much longer than the blade 6 and would prevent establishing circuit connections; and, in the second place, the blade 6 is placed at right angles to the blade 3 and provided with an enlarged curl 7, so that it would not enter a standard socket. This arrangement renders it impossible to insert the base portion by itself into a standard socket and use the device without fuse protection. The fuse may be removed by simply applying a new body portion complete. This portion is simple and cheap to manufacture and can, therefore, be sup-

plied at a very slight cost. If made of glass or similar material, the condition of the fuse can be easily seen at any time.

The arrangement of the clips 13 with short arms and the projections 14 adapted to engage the curl 7 of the contact 6, provides that, when the parts are in assembled relation, the base and the body are held together firmly so as to require more force for their separation than is required to pull the blades 75 3 and 15 out of their sockets. Accordingly, if the user should attempt to remove the plug from its socket by simply pulling on the cord, as is frequently done, the blades 3 and 15 would be released from their sockets before the blade 6 could be pulled out of the socket 13. This provides for keeping the assembly of the base 1 and the body 8 intact until it is necessary to renew a fuse. In the latter case, little additional force will separate the base and the body.

This construction also makes it a simple matter to connect this plug to the circuit conductors. By simply removing the body portion, the terminals of the contacts 3 and 6 are exposed so that connections may be made in the usual manner.

It will be seen that, while the assembled unit provides a plug, having contact blades projecting therefrom in the usual manner 95 and arranged to fit a standard socket, the separation of the body from the base renders the device unfit for use until a new fuse or a new fuse member has been assembled in its stead.

This plug will, therefore, serve as complete protection for the appliance to which it is connected, to guard against the use of the same without a proper fuse in the circuit.

While the device has been described as a 105 unitary plug, it will be understood, of course, that sub-combinations thereof may be found useful by themselves, and the use of such sub-combinations is contemplated by this invention. It is further obvious that various 110 changes may be made, within the scope of the appended claims, in the details of construction without departing from the spirit of this invention; it is, therefore, to be understood that this invention is not limited to 115 the specific details shown and described.

Having thus described the invention, what is claimed is:

1. An electric attachment plug, comprising, a base portion, a body portion adapted for assembly therewith, a pair of contact blades projecting from said body portion and adapted for connection to circuit conductors at said base, one of said blades being mounted on said base and the other on said body, and a fuse interposed in the circuit of said latter blade and permanently mounted on said body.

2. An electric attachment plug, comprising, a base portion, a body portion adapted for assembly therewith, a pair of contact 130

- blades projecting from said body, one of said blades being mounted on said base and extending through said body, and a fuse permanently on said body interposed in the circuit of one of said blades. 5. An electric attachment plug, comprising, a base portion, a body portion adapted for assembly therewith, said body having a fuse permanently mounted thereon and providing a renewable fuse member, a pair of contact blades projecting from said body, one of which is mounted on said base, and means completing the electric circuit through said fuse. 10. 3. An electric attachment plug, comprising, a base portion having a pair of contact blades adapted for connection to a circuit conductor, a body portion adapted for assembly with said base portion and provided with a passage therethrough for one of said blades and a contact socket adapted to receive the second blade, a third contact blade on said body portion, and a fuse on said body portion connecting said socket with said third blade. 15. 4. An electric attachment plug, comprising, a base portion having a pair of contact blades adapted for connection to a circuit conductor, a body portion adapted for assembly with said base portion and provided with a passage therethrough for one of said blades and a contact socket adapted to receive the second blade, a third contact blade on said body portion, and a fuse on said body portion connecting said socket with said third blade. 20. 20. 5. An electric attachment plug, comprising, a base portion, a body portion adapted for assembly therewith, said body having a fuse thereon and providing a renewable fuse member, a pair of contact blades projecting from said body, a plug socket adapted to receive and hold said blades, and means including a spring clip adapted to hold said base and said body in assembled relation with a force greater than that required to pull said blades from said socket. 25. 35. 6. An electric attachment plug, comprising, a base portion, a body portion adapted for assembly therewith, said body having a fuse thereon and providing a renewable fuse member, a pair of contact blades projecting from said body, one of said blades being mounted on said base and the second on said body, and a third blade on said base adapted to engage a socket on said body to hold said parts in assembled relation. 40. 45. 7. An electric attachment plug, comprising, a base portion, a body portion adapted for assembly therewith, a contact blade on said base projecting thru said body, a second contact blade on said base, a clip on said body engageable with said second contact, a third contact blade projecting from said body, and a fuse mounted on said body and connecting said third contact with said clip. 50. 55. 8. An electric attachment plug, comprising, a base portion having a long and a short contact blade thereon adapted for connection to circuit conductors, a body portion adapted for assembly with said base having a fuse mounted therein and provided with a passage therethru for said long contact blade, a clip on said body engageable with said short contact and connected to one end of said fuse, and a third contact blade projecting from 60. 65. 70. 75. 80. 85. 90. 95. 100. 105. 110. 115. 120. 125. 130.
- said body and connected to the other end of said fuse.
- In testimony whereof I affix my signature this 9th day of April, 1928.
- JOHN C. SAMPSON. 70
